UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

CONDENSER FOR REFRIGERATING APPARATUS

Application filed June 3, 1927. Serial No. 196,300.

This invention relates to mechanical refrigerating apparatus, and more particularly to condensers therefor.

An object of my invention is to provide a condenser in which gaseous refrigerant will be quickly and efficiently transformed to liquid refrigerant by the circulation of air.

A further object of my invention is to efficiently condense gaseous refrigerant in a mechanical refrigerating apparatus by the provision of a condenser in which the gaseous refrigerant circulates until condensed whereupon it falls by gravity into the condenser reservoir.

Other objects of the invention, more or less incidental or ancillary to the foregoing will appear in the following description which sets forth in connection with the accompanying drawings a preferred embodiment of the invention.

In the accompanying drawings:

Figure 1 is a plan view of refrigerating apparatus in which my invention is incorporated.

Figure 2 is a front elevation of the same.

Figure 3 is a front elevation of a modified form of condenser.

Referring now to the drawings by characters of reference, 10 represents a support upon which mechanical refrigerating mechanism with which my invention is incorporated is mounted. A drive motor 14 and a compressor 13 are arranged in spaced relation upon the rear side of the support 10 and a drive belt 15 extends around the pulley 24 on the motor shaft and the fan pulley wheel 9 which is fixed to the compressor crank shaft 8. An air circulating fan 23 is secured to the end of the motor drive shaft and projects beyond the belt driven pulley 24.

A refrigerant condenser structure is mounted upon the support 10 in spaced relation and parallel with the fan 23 so that the air circulated by the fan will be blown against the condenser structure to absorb heat from the refrigerant therein. The condenser structure consists of a vertically extending header 12 which serves as a reservoir for the condensed refrigerant, and condensing tube sections 21 which are preferably

substantially circular in form. The ends of the circular condensing tubes are secured to opposite sides of the vertically extending header and are arranged in open communication with the interior of the header. The circular condensing tubes are preferably of different diameters and extend in a single vertical plane parallel to the fan 23 and the ends of the tube sections are preferably in alignment. The condensing pipe sections are preferably provided with spiral fins 22 in order to increase the heat transfer capacity thereof.

The condenser header is provided with a connection 11 in its upper end to which a conduit 17 is connected. The conduit 17 is also connected to the outlet 16 of the compressor, and serves to conduct compressed refrigerant from the compressor into the upper portion of the condenser header. An outlet connection 19 leads from adjacent the bottom of the condenser header and a conduit 20 extends from the connection 19 to a refrigerant expansion apparatus (not shown). The refrigerating apparatus herein illustrated, with the exception of the condenser structure, is of the conventional compressor-condenser-evaporator type and a description of the cycle of operation of such a system is not deemed necessary to clearly understand this invention.

In Figure 3, illustrating the modified form of condenser structure, the header 12 is similar to that previously described but the condensing pipe sections 31 are formed to extend in a semi-circle and the ends thereof are attached to opposite sides of the header. It necessarily shows that with this modified form of condenser structure that the header 12 must be considerably elongated relative to that employed when the condensing tubes are substantially circular.

It will be seen that the compressed gaseous refrigerant is introduced into the upper portion of the vertically extending header and will circulate in the condensing tube sections until condensed, whereupon the liquid refrigerant will flow by gravity into the lower portion of the header which serves as a reservoir for the liquid refrigerant. The con-

densing tube sections are spaced apart and cover a large area within which air is circulated by the fan 23 so that the gaseous refrigerant is quickly and efficiently condensed.

5 Various changes can be made in the construction of the apparatus herein described without departing from the spirit of my invention and the scope of what is claimed.

What I claim is:

10 1. An air cooled refrigerant condenser comprising a vertically extending header for distributing gaseous refrigerant and storing condensed refrigerant, and condenser tube sections each having their ends communicating

15 with and secured on opposite sides of and to the upper portion of said header, said tube sections being arranged to permit compressed refrigerant to flow therein from said header and to flow by gravity back into said header

20 when condensed.

2. An air cooled refrigerant condenser comprising a plurality of curved, concentrically disposed condensing tube sections extending substantially in a vertical plane, and a header 25 extending intermediate the ends of each of said tube sections, the ends of said tube sections being in open communication with, and secured to, said header.

3. An air cooled refrigerant condenser comprising a header and tube sections secured together in open communication, said header and tube sections being arranged to permit gaseous refrigerant from the compressor to flow substantially in circles and to drain by 35 gravity into the bottom of said header when condensed.

4. An air cooled refrigerant condenser comprising a vertically extending header, and a plurality of concentrically disposed tube sections each having their ends secured to opposite sides of said header and in open communication therewith.

40 5. An air cooled refrigerant condenser comprising a header and tube sections secured together in open communication, said tube sections being bent into circular form and extending in a vertical plane, said header and tube sections being arranged to permit gaseous refrigerant to flow substantially in circles 50 while being condensed and to drain by gravity into the bottom of said header when condensed.

In testimony whereof I hereunto affix my signature.

CHARLES C. SPREEN.
